SHOE SUPPORT

John F. Standish, Winthrop, Mass., assignor to
United Shoe Machinery Corporation, Paterson,
N. J., a Corporation of New Jersey

Application March 27, 1931. Serial No. 525,821

13 Claims. (Cl. 1—32.)

This invention relates to shoe-supports and more particularly to the jacks of heel-attaching machines.

It is important, in nailing the heels of shoes, that the bed-plate situated at the extremity of the jack-post, and which is engaged by the ends of the cones of lasts within the shoes being operated upon, shall be not less in area than said cone-ends and shall register with or afford full contact for them. This is to prevent the cones from being broken at projecting edges by the forcing of the bed-plate into them under the clamping pressure applied to the work in preparation for the insertion of the nails. While a bed-plate of a suitable size for the work in hand may be attached to the usual jack-post, when shoes are small, as those for children, and have a high leg-portion or top furnished by the quarters, it is difficult to apply the work to the jack, because of interference between this leg-portion and the jack-elements adjacent to the bed-plate. Reduction of the transverse dimensions of the jack to avoid this interference is prevented by the presence of adjusting means which provide for the proper positioning of the shoe and which are disturbed by such changes. An object of the present invention is to furnish a support for shoes of the character just mentioned, in which, with the proper contact-receiving area upon the jack for the last-cones, the work may easily be applied, such support also including all desirable adjustments unaffected by the presence of the work. To this end, I combine in a novel manner with a jack-post, a last-bed-plate and a mounting member for the bed-plate extending therefrom through a shoe supported upon the post. The mounting member is preferably smaller in its transverse dimensions longitudinally of the jacked shoe that is the contact-area between the last-cone and bed-plate. There is thus furnished about the mounting member a space into which the top of the shoe may project without being strained or offering resistance to its jacking by the operator. The extension of the mounting member through the shoe-top allows the various adjusting means, which would be interfered with were they close to the bed-plate, to be successfully located entirely clear of the work. Certain of these adjustments involving the mounting member or members and the bed-plate itself furnish features of the invention, regardless of the specific character of the bed-plate-mounting with which they are associated.

One of the several forms which my invention may assume is illustrated in the accompanying drawing, in which

Fig. 1 is a perspective view of my improved last-bed-plate, its mounting and the more directly co-operating elements of a heel-attaching machine;

Fig. 2, a side elevation with parts broken away and in section; and

Figs. 3 and 4, sections upon the lines III—III and IV—IV, respectively, of Fig. 2.

At 10 appears a portion of the frame of a heel-attaching machine, such as that of Letters Patent of the United States No. 1,157,688, Glidden, October 26, 1915, in which is mounted a die-block 12 and upon which is shown as movable a holder 14 for the heels H to be attached. A shoe S to be heeled is supported upon a jack-post 16 pivoted upon the frame, as illustrated in the patent just mentioned. The jacked shoe is located in the correct nailing position above the heel-holder and die-block by engagement with a band-clamp 17, a small portion only of which appears in the drawing. To bring the heel-seat of the jacked shoe to the proper inclination longitudinally of said shoe with respect to the upper surface of a heel carried by the holder 14, the end of the post is divided at 18, there being 80 adjustably mounted therein a block 20 movable about and clamped by a transverse screw 22 and locked by intermeshing corrugations at 24. This jack-post-end is as disclosed in Patent No. 1,133,533, Buckminster, March 30, 1915. Extending laterally of the lower extremity of the post are dovetailed ways 26 receiving a complementally inclined projection 28 from a slide 30. The projection, instead of having extended engagement with the ways, is curved at its periphery at 32, preferably about arcs of a circle having its center midway of the projection. This permits the slide to turn about an axis extending longitudinally of the post, as well as to shift laterally. The element 30 is separably retained against accidental displacement from the block 20 by a spring-actuated latch 34 movable in said block and entering a slot 36 in the slide. At the under side of the slide 30 is shown a guide-projection 38 extending from front to rear of the post, this projection fitting within ways 40 is an elongated mounting member 42. A screw 44 threaded vertically through the slide has a cylindrical end-portion 46 lying within a slot 48 in the mounting member and limiting the extent of movement of the member upon the slide. The mounting member 42 is not only tapered laterally in a downward direction, but is also reduced transversely from front to rear, having an inwardly and downwardly inclined wall 50 at its 110

forward side and being inwardly curved at 52 at its rear. This form, as will later more clearly appear, allows the mounting member to freely receive the leg-portion of a high shoe, as the 5 last within the shoe is brought into engagement with the bed-plate. A considerable vertical portion of the member 42 is unbroken, giving the full strength of the metal to resist the pressure applied in the heeling operation; but near its 10 lower end it has a lateral slot 54 receiving an upward laterally extended projection 56 from a bed-plate 58. From front to rear of the mounting member extends a groove or arcuate depression 60, in which fits the complementally curved surface 62 of the plate, these surfaces taking the thrust of the applied pressure of the machine, yet allowing the plate to tilt laterally. The projection 56 holds the plate against displacement, having in it an arcuate slot 64 receiving the cylindrical end 66 of a screw 68 threaded horizontally into the holder, with its head countersunk at the front. This tiltable mounting, it will be observed, produces no increase in the dimensions of the member 42 from front to rear, and but slightly 25 enlarges laterally this portion of the support. At the bottom of the bed-plate 58 is a plane surface 70 arranged for contact with the end of a cone of a last L within the shoe S. From this surface depends a pin 72 to enter the last-opening 1 and position said work transversely of the plate. About the periphery of the bed-plate is an inclined surface diverging upwardly and outwardly from the surface 70 and forming a projection 74, this serving to hold the top of the jacked shoe away from the upper extremity of the last-cone and thus prevent the top from being pinched between the last and the bed-plate.

In using the work-support of this invention, the operator, with the jack drawn forward from 40 above the die-block and heel-holder, applies the lasted shoe S to the pin 72 upon the plate 58, the projection 74 holding the shoe-top away from the contacting surfaces of the plate and last-cone, and the laterally reduced plate-mounting 45 42 receiving the upper extremity of the top within its contracted portion, without throwing any strain upon the work as the last is settled in place upon the pin. The jack-post is then swung into the nailing position appearing in Figs. 1 and 2 of the drawing, and the shoe is correctly 50 located by its engagement with the band-clamp 17 with reference to the heel H, which has been inserted in the holder 14, and to the nail-passages 80 in the die-block 12. Movement of the mounting slide 30 along the ways 40 of the member 42 enables the operator to carry the jack-post back 55 against its stop after the rearward travel of the work, bed-plate and mounting means has been stopped by the band-clamp. Shifting the slide 60 longitudinally of the ways 26 provides for the proper introduction of the work into the band-clamp. The turning of the last about the pin 72 to correctly present the lasted shoe to the heel tends to throw the top of the last-cone out of registration 65 with the bed-plate-surface 70. This condition the operator may correct by rotating the projection 28 of the slide 30 in the ways 26 to the necessary extent, or until no part of the contact-surface of the cone lies outside the plate. Crushing 70 and mutilation of the last is thus avoided. The oscillation of the bed-plate 58 about the pivot 66 on the mounting member, upon the application of clamping pressure by the heeling machine, compensates for the lack of parallelism between the 75 end of the last-cone and the general plane of

the heel-seat of the jacked shoe. None of these adjustments is interfered with by the upward extension of the shoe-top above the bed-plate, nor is it necessary to weaken the elements containing the adjustable connections, because of the reduction in diameter, to receive the top. When small shoes calling for the use of my invention are to be heeled, no change is necessary in the standard jack-post employed for larger work, since the mounting elements of the smaller bed-plates are interchangeable in the ways 26 of the post. The bed-plates of this invention may quickly be substituted for one another, together with their mounting members 38 and 42, by release of the single latch 34 manipulated directly from the operator's position. This facilitates the employment of a plate of the size best suited for the particular lasts in the shoes being operated upon.

Having described my invention, what I claim as new and desire to secure by Letters Patent of the United States is:

1. In a shoe-support, the combination with a jack-post, of a bed-plate arranged for contact with the cone of a last, a mounting member for the bed-plate arranged to extend therefrom through and outside a jacked lasted shoe, said member being smaller in its transverse dimension longitudinally of the jacked shoe than is the contact-area between the last-cone and bed-plate, 105 and a slide movable on the jack-post and carrying the mounting member.

2. In a shoe-support, the combination with a jack-post, of a bed-plate arranged for contact with the cone of a last, a mounting member for the bed-plate arranged to extend therefrom through a jacked lasted shoe, said member being smaller in its transverse dimension longitudinally of the jacked shoe than is the contact-area between the last-cone and bed-plate, 110 and a slide movable on the jack-post, the mounting member being movable upon the slide.

3. In a shoe-support, the combination with a jack-post, of a bed-plate arranged for contact with the cone of a last, a mounting member for the bed-plate arranged to extend therefrom through and outside a jacked lasted shoe, a slide movable on the jack-post and carrying the mounting member, and pivotal connections between the bed-plate and mounting member. 125

4. In a shoe-support, the combination with a jack-post, of a bed-plate arranged for contact with the cone of a last, a mounting member for the bed-plate arranged to extend therefrom through a jacked lasted shoe, and connections between the mounting member and jack-post arranged to permit said member to turn about an axis extending longitudinally of the jack-post. 130

5. In a shoe-support, the combination with a jack-post, of a bed-plate arranged for contact with the cone of a last, a mounting member for the bed-plate arranged to extend therefrom through a jacked lasted shoe, and a slide movable on the jack-post and carrying the mounting member and being free to turn about an axis extending longitudinally of the jack-post. 140

6. In a shoe-support, the combination with a jack-post, of a bed-plate arranged for contact with the cone of a last, a mounting member for the bed-plate arranged to extend therefrom through a jacked lasted shoe, a slide movable on the jack-post and carrying the mounting member and being free to turn about an axis extending longitudinally of the jack-post, and 150

- 30 pivotal connections between the bed-plate and mounting member.
- 35 7. In a shoe-support, the combination with a jack-post, of a bed-plate arranged for contact with the cone of a last, and a mounting member for the bed-plate arranged to extend therefrom through a jacked shoe and supported upon the jack-post, said member being smaller in its transverse dimension longitudinally of the jacked shoe than is the contact-area between the last-cone and bed-plate and having a surface diverging outwardly from the cone of the last beyond the contact-area of the bed-plate.
- 40 8. In a shoe-support, the combination with a jack-post, of a mounting member movable thereon, a pivot-pin carried by the mounting member, and a last-bed-plate arranged to tilt upon the pin and retained in place thereby upon the mounting member.
- 45 9. In a shoe-support, the combination with a jack-post, of a mounting member movable thereon, a screw threaded into the front of the mounting member and having a cylindrical inner end, and a last-bed-plate provided with a perforated lug pivoted upon the screw-end.
- 50 10. In a shoe-support, the combination with a jack-post having ways, of a slide movable in said ways and being provided with ways, a mounting member movable in the slide-ways, a last-bed-plate pivoted upon the mounting member.
- 55 11. In a shoe-support, the combination with a jack-post having ways, of a member movable longitudinally of the ways and arranged to turn therein about an axis extending longitudinally of the jack-post, and a last-bed-plate carried by the member.
- 60 12. In a shoe-support, the combination with a jack-post having ways, of a slide having a portion entering the ways and arranged to move longitudinally thereof and to turn therein, said slide being provided with ways, a mounting member movable in the slide-ways, and a last-bed-plate pivoted upon the mounting member.
- 65 13. In a shoe-support, the combination with a jack-post having ways extending laterally of the post, of a slide having a portion entering the ways and arranged to move longitudinally thereof and to turn therein, said slide being provided with ways extending from front to rear of the post, a mounting member movable in the slide-ways, and a last-bed-plate pivoted upon the mounting member to tilt laterally thereof.
